CLAIM

I claim the ornamental design for a noodle, as shown and described.

DESCRIPTION

FIG. 1 is a front top perspective view of a first embodiment of a noodle;

FIG. 2 is a top view of the first embodiment thereof;

FIG. 3 is a right side view of the first embodiment thereof;

FIG. 4 is a left side view of the first embodiment thereof;

FIG. 5 is a bottom view of the first embodiment thereof;

FIG. 6 is an end view of the first embodiment thereof;

FIG. 7 is a cross-sectional view of the first embodiment thereof taken from line 7-7 shown in FIG. 1;

FIG. 8 is a front top perspective view of a second embodiment of a noodle;

FIG. 9 is a top view of the second embodiment thereof;

FIG. 10 is a right side view of the second embodiment thereof;

FIG. 11 is a left side view of the second embodiment thereof;

FIG. 12 is a bottom view of the second embodiment thereof;

FIG. 13 is an end view of the second embodiment thereof; and,

FIG. 14 is a cross-sectional view the second embodiment thereof taken from line 14-14 shown in FIG. 8.

The break lines shown in the middle portion of the noodle in FIGS. 8-14 indicate that the appearance of any portion of the article between the break lines forms no part of the claimed design.
